Primary Examiner — Ricky Pham(74) *Attorney, Agent, or Firm* — Millen White Zelano & Branigan, P.C.(57) **CLAIM**

The ornamental design for a cutting board, as shown and described.

DESCRIPTION

FIG. 1 is a top perspective view showing the bottom most cutting board showing our new design.

FIG. 2 is another top perspective view thereof.

FIG. 3 is a top view thereof.

FIG. 4 is bottom view thereof.

FIG. 5 is a side view thereof.

FIG. 6 is another side view thereof.

FIG. 7 is a front side view thereof; and,

FIG. 8 is a back view thereof.

The broken lines in the drawings illustrate portions of the cutting board which form no part of the claimed design.
